QUATERNARY AMMONIUM COMPOUNDS CONTAINING THE 8-(6-CHLORO-1,3-BENZODIOXY-ANYL)METHYL GROUP

Chien-Pen Lo, Philadelphia, Pa., assignor to Rohm & Haas Company, Philadelphia, Pa., a corporation of Delaware.

Delaware No Drawing. Filed Aug. 28, 1959, Ser. No. 836,583
6 Claims. (Cl. 260—340.3)

This invention concerns quaternary ammonium compounds of the formula

wherein X is an anion, R¹ is a lipophilic group, including alkyl groups of at least 10 carbon atoms, preferably 12 to 20 carbon atoms, alkenyl groups of 11 to 18 carbon atoms, and arylaliphatic groups having at least 12 carbon atoms, preferably 15 to 25 carbon atoms, and R² and R³, when taken individually, represent alkyl groups of one to two carbon atoms, the hydroxyethyl group, or a benzyl group, and when taken together, form a divalent aliphatic chain of four to five atoms which with the nitrogen forms a heterocycle, such as

$$\begin{array}{c}
 \text{---CH}_2\text{CH}_2\text{CH}_2\text{CH}_2\text{---} \\
 \text{---CH}_2\text{CH}_2\text{CH}_2\text{CH}_2\text{CH}_2\text{---} \\
 \text{---CH}_2\text{CH}_2\text{OCH}_2\text{CH}_2\text{---} \\
 \text{---CH}_2\text{CH}_2\text{SCH}_2\text{CH}_2\text{---}
 \end{array}$$

OR

or the corresponding lower alkyl-substituted chains, as found in the C-methylpyrrolidine, C-methylpiperidine, or C-methylmorpholine groups.

The lipophilic groups, R^1 , may be given a variety of types and structures with retention of the desirable combination of properties afforded by the quaternary compounds of this invention. Thus, there may be used an N-alkyl group, such as decyl, undecyl, dodecyl, tetradecyl, hexadecyl, heptadecyl, octadecyl, or eicosyl, whether of straight or branched chain, N-alkenyl such as undecenyl, dodecenyl, or oleyl, aliphatic hydrocarbon chains interrupted by ether groups as in octyloxypentenyl or nonyloxy pentenyl or an N-arylaliphatic group such as diethylbenzyl, octylbenzyl, nonylbenzyl, dodecylbenzyl, pentadecylbenzyl, octadecylbenzyl, octylmethylbenzyl, or octyldimethylbenzyl, trimethylphenylpentenyl

$$((\text{CH}_3)_3\text{C}_6\text{H}_2\text{CH}_2\text{CH}_2\text{CH}=\text{CHCH}_2-)$$

or diethylphenylpentenyl, octylmethylphenoxyethoxyethyl or dodecylphenoxyethoxyethyl.

The other N-substituents forming the quaternary group also have considerable latitude and may be ethyl, methyl, or other lower alkyl group, benzyl, chlorobenzyl, dichlorobenzyl, methylbenzyl, phenoxyethyl, ethoxyethyl, hydroxyethyl, or hydroxypropyl, when taken individually. Together R^2 and R^3 may form a divalent chain, such as found in morpholine, 2-methyl- or 2,6-dimethyl-morpholine, thiamorpholine, pyrrolidine, or piperidine.

The anion X^- is most commonly chlorine but may equally well be bromine and such a halogen may be replaced with sulfate, phosphate, methyl sulfate, nitrate, acetate, and so on, by conventional steps.

These quaternary ammonium compounds are characterized by possessing fungicidal properties together with low phytotoxicity for living plants.

2

The bactericidal action of surface-active quaternary ammonium salts has long been recognized. Some of the known quaternary ammonium compounds have also exhibited action against fungi. Attempts have been made to utilize various types of quaternary ammonium salts on plants but without the development of any practical applications in the field of plant protection. This lack of practical application in this field has been due in large part to the relatively severe phytotoxicity of previously known quaternary ammonium compounds, some of which have also been lacking in tenacity or persistence on plants.

As typical of the observations which have been made with previously known quaternary ammonium compounds, it may be mentioned that when young tomato plants in the greenhouse were sprayed with a 1% solution of various known salts, the plants were killed. Compounds giving this result included n-dodecyl(benzyl) dimethylammonium chloride, n-hexadecyl(benzyl) dimethylammonium chloride, t-octylphenoxyethoxyethyl (benzyl)dimethylammonium chloride, t-octylcresoxyethoxyethyl(benzyl)dimethylammonium chloride, t-dodecyltrimethylammonium chloride, (dodecylbenzyl)trimethylammonium chloride, and (dodecylmethylbenzyl) trimethylammonium chloride. Even at concentrations of 0.1% the phytotoxic effects were objectionable.

The object of the present invention is to provide quaternary ammonium compounds which possess fungicidal activity against common plant pathogens and which at the same time have low phytotoxicity. Another object is to furnish compounds which may be used to control apple scab, a use requiring both protectant and eradicant actions.

The above-defined quaternary ammonium salts are prepared by reacting 6-chloro-8-chloromethyl-1,3-benzodioxane with a tertiary amine having at least one lipophilic substituent. Approximately equivalent quantities of the two reactants are mixed, preferably in an organic solvent. The mixture may be heated between about 25° and about 125° C. for a time sufficient to substantially complete the reaction. The solvent is then distilled off to leave a residue in the form of an oil or a paste which may be used without further purification if so desired. Alternatively, the residue may be purified by treatment with charcoal or extraction or in the case of solids, crystallization.

Suitable solvents for the reaction include acetone, methyl hexyl ketone, diethyl ketone, acetonitrile, nitro-methane, ethyl acetate, naphtha, benzene, toluene, or xylene.

50 The preparation of 6-chloro-8-chloromethyl-1,3-benzodioxane has been described by Buehler et al., J. Amer. Chem. Soc. 62, 890 (1940).

Tertiary amines which are reacted with the above compounds supply at least one lipophilic group. In general, such a group will contain at least 10 carbon atoms. The upper limit of carbon atoms is dictated by matters of availability and also of solubility of the final quaternary ammonium salt. Typical tertiary amines include n-dodecyldimethylamine, cetyltrimethylamine, decyltrimethylamine, dodecylbenzylmethylamine, dodecylbenzylamine, N-dodecylmorpholine, N-octadecylmorpholine, N-myristylpyrrolidine, N-cetylpiriperidine, oleyldimethylamine, (5,5,7,7-tetramethyl-2-octenyl)dimethylamine, octyloxypentenylidimethylamine, (octylbenzyl)dimethylamine, dodecylbenzyldimethylamine, octylphenoxyethoxydimethylamine, nonylphenoxyethoxyethylbenzylmethyamine, nonylphenoxyethylhydroxyethylamine, octylphenoxyethoxyethylmorpholine, nonylphenoxyethoxyethylpiriperidine, (diethylphenyl-2-pentenyl)dimethylamine.

Additional details of the preparation of the compounds of this invention are presented in the following illustrative

examples, wherein parts are by weight unless otherwise specified.

EXAMPLE 1

A mixture of 8 parts of 6-chloro-8-chloromethyl-1,3-benzodioxane, 12.4 parts of t-octylphenoxyethoxyethyl dimethylamine, and 80 parts of acetone was refluxed with stirring for 3 hours. The mixture was concentrated under reduced pressure to give 17.5 parts of a viscous oil which corresponded in composition to

Analysis.—Calcd. for $\text{C}_{29}\text{H}_{43}\text{Cl}_2\text{NO}_4$: N, 2.6. Found: N, 2.5.

In the fungitoxicity test (slide-germination method), [8 - (6-chloro-1,3-benzodioxanyl)methyl]- (t-octylphenoxyethoxyethyl)-dimethylammonium chloride gave ED_{50} values of 5-10 p.p.m. against *Monolinia fructicola* and of less than 5 p.p.m. against *Stemphylium sarcinaeforme*.

On tomato plants, it showed slight injury at 1%, but no injury at 0.1%.

In the greenhouse test against apple scab (*Venturia inequalis*) on apple seedlings (McIntosh), this compound gave 92% protection at 0.75 lb. per 100 gallons and 80% protection at 0.25 lb. per 100 gallons, and 51% eradication at 0.75 lb. per 100 gallons.

In the greenhouse test against late blight (*Phytophthora infestans*) on tomatoes, this compound showed excellent performance, having an ED_{50} value of 53 p.p.m. against 480 p.p.m. for zineb as a standard. There was no injury shown at 1 lb. per 100 gallons.

The corresponding compounds in which the two N-methyl groups are replaced by ethyl groups or hydroxyethyl have almost the same properties as the above quaternary ammonium salt. Likewise, there may be used the benzyl group as an N-substituent to give again closely related compounds.

EXAMPLE 2

A mixture of 17.5 parts of 6-chloro-8-chloromethyl-1,3-benzodioxane, 20.9 parts of (nonylbenzyl)dimethylamine, and 120 parts of acetone was refluxed with stirring for 3.5 hours. The solid was cooled, whereupon it separated. It was filtered off, washed with acetone, and dried in air. There was obtained 30 parts of a product which melted at 126-128° C. and has the structure

Analysis.—Calcd. for $\text{C}_{27}\text{H}_{39}\text{Cl}_2\text{NO}_2$: Cl, 14.8; N, 2.9. Found: Cl, 14.9; N, 2.8.

In the fungitoxicity test (slide-germination method), [8 - (6 - chloro-1,3-benzodioxanyl)methyl]- (nonylbenzyl) dimethylammonium chloride gave the following ED_{50} values: 1-10 p.p.m. against both *Alternaria solani* and *Monolinia fructicola* and less than 1 p.p.m. against *Stemphylium sarcinaeforme*.

Replacement of (nonylbenzyl)dimethylamine with an equivalent weight of N-nonylbenzylmorpholine gives (8-(6-chloro-1,3-benzodioxanyl)methyl)nonylbenzylmorpholinium chloride, which has ED_{50} values against the same test organisms at least as favorable as the above quaternary ammonium chloride. In the same way, there may be used nonylbenzylpiperidine or nonylbenzylpyrrolidine to give corresponding piperidinium and pyrrolidinium chlorides of similar activity and low phytotoxicity.

EXAMPLE 3

A mixture of 10 parts of 6-chloro-8-chloromethyl-1,3-

benzodioxane, 13.9 parts of dodecylbenzyldimethylamine, and 80 parts of acetone was refluxed with stirring for 3.5 hours. After the solvent was removed under reduced pressure, there was obtained 24 parts of a viscous oil which corresponded in composition to

Analysis.—Calcd. for $\text{C}_{30}\text{H}_{45}\text{Cl}_2\text{NO}_2$: N, 2.7. Found: N, 2.6.

15 In the fungitoxicity test (slide-germination method), [8 - (chloro-1,3-benzodioxanyl)methyl]- (dodecylbenzyl) dimethylammonium chloride gave ED_{50} values of less than 5 p.p.m. against both *Monolinia fructicola* and *Stemphylium sarcinaeforme*.

20 On tomato plants, it showed no injury even at 1%.

In the greenhouse test against apple scab (*Venturia inequalis*) on apple seedlings (McIntosh), this compound gave complete protection at 0.75 lb. per 100 gallons and 91% protection at 0.25 lb. per 100 gallons, and 92% eradication at 0.75 lb. per 100 gallons.

25 In the greenhouse test against late blight (*Phytophthora infestans*) on tomatoes, this compound showed excellent performance, having an ED_{50} value of 33 p.p.m. against an ED_{50} value of 480 p.p.m. for zineb as a standard 30 under the same conditions. There was not injury shown at 1 lb. per 100 gallons.

The comparable compound having two ethyl groups in place of the methyl groups is likewise free of phytotoxic effects at normal use concentrations and of almost the 35 same activity against *Venturia inequalis* and *phytophthora infestans*.

EXAMPLE 4

A mixture of 21.9 parts of 6-chloro-8-chloromethyl-1,3-benzodioxane, 33 parts (96.4%) of dodecylmethylbenzyl dimethylamine, and 120 parts of acetone was stirred and heated under reflux for 3 hours. The mixture was concentrated under reduced pressure to give 51 parts of a viscous oil which corresponded in composition to

Analysis.—Calcd. for $\text{C}_{31}\text{H}_{47}\text{Cl}_2\text{NO}_2$: Cl, 13.3; N, 2.6. Found: Cl, 13.4; N, 2.6.

55 In the fungitoxicity test, [8 - (6-chloro-1,3-benzodioxanyl)-methyl]dodecylmethylbenzyl dimethylammonium chloride gave ED_{50} values of 1-10 p.p.m. against *Alternaria solani*, *Monolinia fructicola*, and *Stemphylium sarcinaeforme*.

EXAMPLE 5

60 A mixture of 10 parts of 6-chloro-8-chloromethyl-1,3-benzodioxane, 13.6 parts of n-octadecyldimethylamine, and 80 parts of acetone was heated under reflux with stirring for 2 hours. The mixture was cooled, and a solid separated. This was filtered off, washed with acetone, and dried in air. There was obtained 18 parts of a product which melted at about 90° C. and has the structure of

Analysis.—Calcd. for $C_{20}H_{31}Cl_2NO_2$: N, 2.7. Found: N, 2.9.

In the fungitoxicity test (slide-germination method), [8-(6-chloro-1,3-benzodioxanyl)methyl]-n-octadecyl-dimethylammonium chloride gave ED_{50} values of 5-10 p.p.m. against *Stemphylium sarcinaeforme* and of less than 5 p.p.m. against *Monolinia fructicola*.

On tomato plants, it showed moderate injury at 1% but no injury at 0.1%.

Replacement of the above N-methyl groups with ethyl or hydroxyethyl groups gives quaternary salts of the same characteristics, but of even greater safety on tender plants.

EXAMPLE 6

The alkyldimethylamine used in this experiment had the following composition:

40% n-dodecyldimethylamine
50% n-tetradecyldimethylamine
10% n-hexadecyldimethylamine

A mixture of 24.2 parts of the alkyldimethylamine, 21.9 parts of 6-chloro-8-chloromethyl-1,3-benzodioxane, and 120 parts of acetone was stirred and heated under reflux for 4 hours. The mixture was concentrated under reduced pressure to give 45 parts of a viscous oil which corresponded in composition to

wherein R represents alkyl groups from C_{12} to C_{16} .

Analysis.—Calcd. for

$C_{23}H_{38}Cl_2NO_2$ (40%) + $C_{25}H_{43}Cl_2NO_2$ (50%) + $C_{27}H_{47}Cl_2NO_2$ (10%):

Cl, 14.8; N, 2.9. Found: Cl, 15.4; N, 3.0.

In the fungitoxicity test (slide-germination method), the above [8-(6-chloro-1,3-benzodioxanyl)methyl]-alkyl-dimethylammonium chloride gave ED_{50} values of 1-10 p.p.m. against *Alternaria solani*, *Monolinia fructicola*, and *Stemphylium sarcinaeforme*.

EXAMPLE 7

A mixture of 11 parts of 6-chloro-8-chloromethyl-1,3-benzodioxane, 10.1 parts of (5,5,7,7-tetramethyl-2-octenyl)dimethylamine, and 120 parts of acetone was refluxed with stirring for 3.5 hours. The solvent was removed, and there was a residual semi-solid which was triturated with warm ether. The solid thus separated was filtered off, washed, with ether, and dried. There was obtained 18.3 parts of a product which melted at 110-112° and has the structure

Analysis.—Calcd. for $C_{23}H_{37}Cl_2NO_2$: Cl, 16.5; N, 3.3. Found: Cl, 16.0; N, 3.2.

In the fungitoxicity test (slide germination method), [8-(6-chloro-1,3-benzodioxanyl)methyl]-[5,5,7,7-tetramethyl-2-octenyl]dimethylammonium chloride gave ED_{50} values of 10-50 p.p.m. against *Monolinia fructicola* and 5-10 p.p.m. against *Stemphylium sarcinaeforme*.

Replacement of the above 5,5,7,7-tetramethyl-2-octenyl group with other long-chained alkenyl groups or aralkyl-

enyl groups such as previously noted, gives compounds at least as active as the above quaternary and of similar safety to living plants. Thus, there may be used the undecenyl group or the oleyl group with entirely satisfactory results.

The quaternary ammonium compounds of this invention appear stable in light and in air. There is evidence that they have anthelmintic properties and can act as snailicides. For the latter purpose they may be used from aqueous solution or they may be mixed with a solid carrier, such as clay, diatomaceous earth, pyrophyllite, or talc, at concentrations of 5% to 50%. They may also serve against bacteria.

These compounds were examined for their bacteriostatic and bactericidal effects by the standard broth titer test, also known as the tube dilution test, (see page 71 of *Surface-Active Quaternary Ammonium Germicides*, Carl A. Lorentz, Academic Press, New York, 1950). In this test, the agent under test is successively diluted in 20 broth in a series of tubes. The solutions are sterilized and inoculated with a test organism. The inoculated tubes are incubated for 24 hours at 37° C. The last dilution is noted at which no growth occurs. This is the bacteriostatic titer.

25 From the last dilutions which fail to show growth, transfers are made to sterile broth containing an inactivator for quaternary ammonium salts, here lecithin. These tubes are incubated and examined for growth. The last dilution to show no growth gives the bactericidal titer.

30 Summary of results is given in Table I.

Table I
SUMMARY OF TITER TESTS

35	Compound of Example No.	<i>S. typhosa</i>		<i>S. aureus</i>	
		Bacteriostatic Titer	Bactericidal Titer	Bacteriostatic Titer	Bactericidal Titer
40	1.....	1:51, 200	1:51, 200	1:800, 000	1:800, 000
	2.....	1:800, 000	1:200, 000	1:800, 000	1:100, 000

45	7.....	1:6, 400	1:6, 400	1:200, 000	1:12, 800

While in the examples there has been used the chloromethyl group, there may be used in the identical way the bromomethyl group. The resulting quaternary ammonium bromides are at least as effective as the corresponding chlorides and in some instances are more active.

50 As is known in the art, the chloride or bromide ion may be replaced in known ways with other anions. Thus, a concentrated solution of a quaternary ammonium chloride may be treated with a sodium phosphate solution 55 to exchange anions with formation of quaternary ammonium phosphate. Through conversion of halide to hydroxide and subsequent neutralization any anion can be introduced, including acetate or propionate, as typical anions of organic acids. It is thus possible to have present any desired anion.

60 I claim:

1. Compounds of the formula

65 70 wherein X is an inert anion, R^1 is a lipophilic group selected from the class consisting of alkyl groups of 10 to 20 carbon atoms, alkenyl groups of 11 to 18 carbon atoms, alkylbenzyl groups of 15 to 25 carbon atoms, and alkylphenoxyethoxyethyl groups of 15 to 25 carbon atoms,

R^2 and R^3 , when taken individually, represent alkyl groups of one to two carbon atoms, the benzyl group, and the hydroxyethyl group, and R^2 and R^3 , when taken together, represent a saturated divalent aliphatic chain of four to five atoms selected from the class consisting of the $-\text{CH}_2\text{CH}_2\text{CH}_2\text{CH}_2-$, $-\text{CH}_2\text{CH}_2\text{CH}_2\text{CH}_2\text{CH}_2-$, and $-\text{CH}_2\text{CH}_2\text{OCH}_2\text{CH}_2-$ groups which together with the nitrogen atom forms a heterocycle.

2. [8 - (6 - chloro - 1,3 - benzodioxanyl)methyl](tert-octylphenoxyethoxyethyl)dimethylammonium chloride.

10

3. [8 - (chloro - 1,3 - benzodioxanyl)methyl](nonylbenzyl)dimethylammonium chloride.
4. [8 - (6 - chloro - 1,3 - benzodioxanyl)methyl](decylbenzyl)dimethylammonium chloride.
5. [8 - (6 - chloro - 1,3 - benzodioxanyl)methyl](5,5,7,7-tetramethyl-2-octenyl)dimethylammonium chloride.
6. [8 - (6 - chloro - 1,3 - benzodioxanyl)methyl] - n - octadecyldimethylammonium chloride.

No references cited.
